UNITED STATES PATENT OFFICE.

WILLIAM J. LINN, OF PITTSBURGH, PENNSYLVANIA.

SPARK-PLUG.

1,247,975.

Specification of Letters Patent. Patented Nov. 27, 1917.

Application filed January 23, 1917. Serial No. 143,928.

To all whom it may concern:

Be it known that I, WILLIAM J. LINN, a citizen of the United States, residing at Pittsburgh, in the county of Allegheny and 5 State of Pennsylvania, have invented certain new and useful Improvements in Spark-Plugs, of which the following is a specification.

My invention relates to improvements in 10 spark plugs, and has for its primary object to provide an improved spark plug having perfectly protected firing points which constantly scour themselves clean.

Another object of my invention is to provide 15 a spark plug of the type herein described which is gas-tight, oil proof and clean, thereby eliminating short circuiting.

A still further and important object of the invention is to supply a device of the 20 character set forth, provided with an electrode that will assure an intensified spark.

Still further objects of the invention are to provide a spark plug of the type specified which is simple in its construction and arrangement, strong, durable and highly efficient in its use, and comparatively inexpensive to manufacture.

To the accomplishment of these and such other objects as may hereinafter appear, the 25 invention consists of the novel construction, combination and arrangement of parts herein specifically described and illustrated in the accompanying drawing, wherein is shown an embodiment of the invention.

5 In the drawing, forming a portion of this specification and wherein like numerals of reference designate corresponding parts throughout the several views:

Figure 1 is a side elevational view, the 30 one-half portion of which illustrates the outline of a spark plug in accordance with my invention, and the other one-half portion showing a longitudinal cross-section thereof.

Fig. 2 is a perspective view of the center electrode, with the tube containing the mercury partially broken away.

Fig. 3 is an end view of the bushing.

Fig. 4 is a side elevational view of the bushing, showing a portion thereof in cross-section.

Fig. 5 is an end view of the insulator core or porcelain.

Referring more in detail to the drawing there is shown in Fig. 1 my improved spark plug comprising the stock or shell 1, the

insulating core or porcelain 2, the center electrode 3, the bushing 4, the terminal or contact nut 5, the asbestos lined gasket 6 and the firing point 7.

The shell 1 is similar to those now ordinarily in use and is provided with the usual threaded shank 8. In most of the spark plugs now on the market, the insulating core 2 is positioned within the shell so that the end of the insulating core, carrying the electrode firing point 9 is nearly flush with or recedes from the open end of the threaded shank 8. In carrying out the principle of my invention, I position the insulating core 2 within the shell 1 in such a manner that the end 10 thereof will extend decidedly beyond the open end of the threaded shank 8.

The end 10 of the insulating core 2 is further provided with the annular groove 11 and with the slots 12.

By constructing and positioning the insulating core 2, as heretofore described, I have found by actual tests and experiments that the liability of short circuiting is entirely obviated as all accumulations concomitant to its operation are intercepted by the arrangement of the slots 12 and the annular groove 11. Furthermore, the firing point 7 and the electrode firing point 9 will obviously be self-cleaning, owing to the construction of the end 10 of the insulating core 2, which tends to deflect any accumulation that might form thereon.

The center electrode, used in conjunction with my improved spark plug, consists of the metal rods 13^a and 13, which are provided with the threaded ends 14 and 15 respectively, adapted to engage the tapped inner surface 16 of the tube 17. The tube 17 is made from any suitable insulating material, such as fiber, rubber, glass, etc. A small quantity of mercury 18 is imprisoned between the adjacent ends 14 and 15 of the rods 13^a and 13, within the tube 17. Before hermetically sealing the tube 17, the points 14 and 15 are so adjusted to leave the clearance 19 between the mercury 18 and one of the ends 14 or 15, depending on the position of the spark plug.

The mercury 18 is not liable to evaporation as the tube 17, containing the same, is air-tight, and the temperature sufficiently low for its successful operation and stability.

The efficiency of the spark plug is greatly

augmented by the use of the electrode 3 hereinbefore described, as the mercury 18 carried in the tube 17 will intensify the sparking.

6 The electrode 3 is provided with the firing point 9, which has a comparatively large face 20, and when assembled in the insulating core 2, extends slightly beyond the counterbored opening 21 in the end 10 of 10 the insulating core 2, as illustrated in Fig. 1 of the drawing.

15 The electrode 3 is rigidly set, by means of the cement 22 and the compression nut 23, in the hole 24 which extends longitudinally 15 through the insulating core 2.

The insulating core 2 is cushioned against the force of the explosions and is made gas-tight by the lined gasket 6 against one side of the shoulder 25 on the insulating core 2, 20 and by the specially designed bushing 4 against the opposite thereof.

25 The bushing 4 differs materially from any bushing now in use in that it is constructed with a groove 26, forming the inner wall 27 and the outer wall 28. The inner wall 27 is slightly shorter than the outer wall 28 and is provided with the bevel 29.

30 When assembling my improved spark plug the bushing 4 is screwed into the shell 1, and owing to the groove 26 and the beveled inner wall 27 of the bushing 4, the inner wall 27 will readily conform itself to the contour of the shoulder 25 against which it is forced. The construction of my improved 35 bushing 4 obviates the necessity of employing a separate lined gasket on that side of the shoulder 25 against which the bushing 4 is used.

If desired the inner wall 27 of the bushing 40 may be slit in several places, making its conformation to the contour of the shoulder 25 more positive. From actual tests this construction has not been found necessary.

45 As shown in Fig. 1 of the drawing, the firing point 7, attached to the threaded shank 8, extends entirely across the surface 20 of the electrode firing point 9. The firing point 9 may be made detachable from the 50 electrode 3, which would allow the said firing points to be replaced should occasion require it.

The usual threaded end 30, on the electrode 3 is provided for the engagement of 55 the compression nut 23 and the terminal or contact nut 5.

From the foregoing description, taken in connection with the accompanying drawing, the advantages of the construction and of 60 the method of operation will be readily apparent to those skilled in the art to which the invention appertains, and while I have described the principle of operation of the invention, together with the device which I 65 now consider to be the best embodiment

thereof, I desire to have it understood that the device shown is merely illustrative and that such changes may be resorted to when desired as are within the scope of the claims appended hereto.

What I claim is:—

1. A spark plug comprising a shell, a core supported by the shell having a flared extremity, an electrode connected to the shell and passing over the flared extremity, 75 a second electrode supported by the core composed of two members adjustably connected and one of which having a flared extremity opposite said first electrode the flared end of said core being provided with intersecting passages.

2. A spark plug comprising a shell, a core supported by the shell having a flared extremity, an electrode connected to the shell and passing over the flared extremity, a sec- 85 ond electrode supported by the core composed of two members adjustably connected and one of which having a flared extremity opposite said first electrode, said flared end of the core being provided with a circumferential groove and slots intersecting the groove.

3. A spark plug comprising a shell, a core having a flange supported by the shell, a bushing adjustably mounted in the shell 95 and having a grooved flange yieldably engaging said first flange, an electrode connected to the shell, a second electrode supported by the core and composed of two members and a tube supporting the mem- 100 bers for adjustment toward and away from each other and a quantity of conducting fluid supported by the tube between the opposing ends of said member.

4. A spark plug comprising a shell, a core having a flange supported by the shell, a bushing adjustably mounted in the shell and having a grooved flange yieldably engaging said first flange, an electrode connected to the shell, a second electrode supported by 105 the core and composed of two members and a tube supporting the members for adjustment toward and away from each other and a quantity of mercury supported by the tube between the opposing ends of said member 110 and a cementitious material arranged between the members and the core.

5. In a spark plug, an electrode consisting of two members and means for adjustably connecting the members together for varying the distance therebetween.

6. In a spark plug, an electrode consisting of two members and means for adjustably connecting the members together for varying the distance therebetween and a fluid conductor supported between the members by said means.

7. In a spark plug, an electrode consisting of two members and means for adjustably connecting the members together for 13

varying the distance therebetween and mercury supported by said means between the members.

8. In a spark plug, a core forming a central bore, an electrode arranged in the bore consisting of two members adjustably connected and a filler between the electrode and the wall of said bore.

9. In a spark plug, a core forming a central bore, an electrode arranged in the bore consisting of two members adjustably connected and a cementitious material for accomplishing a rigid connection between the members and wall of the bore.

10. In a spark plug, a core forming a central bore, an electrode arranged in the bore consisting of two members, a tube of insulating material having screw threaded engagement with the member and a cementitious material for accomplishing a rigid connection between the members and wall of the bore. 15
20

In testimony whereof I affix my signature in the presence of two witnesses.

WILLIAM J. LINN.
